UNITED STATES PATENT OFFICE.

PETER WEBER, OF NEW YORK, N. Y., ASSIGNOR TO SOHMER & CO., OF NEW YORK, N. Y.,
A FIRM.

CAPO-TASTO BAR FOR PIANOS.

No. 872,487.

Specification of Letters Patent.

Patented Dec. 3, 1907.

Application filed May 24, 1907. Serial No. 375,394.

To all whom it may concern:

Be it known that I, PETER WEBER, a citizen of the United States, residing at New York city, Queens, county of Queens, State 5 of New York, have invented new and useful Improvements in Capo-Tasto Bars for Pianos, of which the following is a specification.

This invention relates to improved means for subdividing from each treble string of a 10 piano an aliquot part of the effective length of such string for the purpose of producing harmonic overtones of the fundamental tone and thereby increasing the brilliancy and volume of the latter. This result is accomplished in a simple and effective manner by 15 means of a double bearing capo-tasto bar having a pair of flanges adapted to span a portion of each treble string and press such portion towards the wrest plank.

20 In the accompanying drawing: Fig. 1 is a cross section of my improved capo-tasto bar showing it applied to a piano; Fig. 2 a face view of the bar; Fig. 3 a bottom view thereof, and Fig. 4 an enlarged cross section on line 25 4—4 Fig. 3.

The capo-tasto bar 5 has a flat body from which extends a front flange 6 and a rear flange 7, both flanges projecting from the bottom of the bar. Flange 7 is divided into a 30 series of stepped sections 8, 9, 10, 11, each section being in turn subdivided into a number of minor steps 12. The length of each section 8—11 is such that it extends across a suitable group of treble strings 13, while 35 each step 12 will accommodate the strings of a single note.

The string plate 14 is provided with a pair of bridges 15, 16, at a distance apart greater than the width of bar 5, such bridges constituting supports for the strings.

In assembling the parts, bar 5 is placed across the treble strings intermediate bridges 15, 16, with its flanges 6, 7, bearing against the strings and facing the string plate. 40 Screws 17 engaging perforations 18 of bar 5, and tapped into the string plate, draw the bar towards the latter and consequently force the strings against the bridges 15, 16, with a pressure that may be readily adjusted.

By the construction described, a portion 50 of each string 13 is freely spanned between the flanges 6, 7, of bar 5 so as to be vibratile intermediate such flanges. The length of this spanned portion should be such that it constitutes an aliquot part of the main or 55 effective length of the string, so that it will sound in harmony therewith. This result is obtained by means of the stepped sections 8 to 11, which are so dimensioned that the length of the spanned portion of any one 60 string in either section forms an aliquot part of the effective length of such string. In other words, the portion of any one string between flange 6 and the inner edge of flange 7, forms an aliquot part of such string between pin 19 of sounding bridge 20 and bridge 15. Thus, with the construction shown, the spanned portions of the strings engaging steps 8, 9, 10, and 11, forms respectively $\frac{1}{2}$, $\frac{1}{3}$, $\frac{1}{4}$ and $\frac{1}{6}$ of the effective length of 70 such strings.

It will be seen that by the means described, the desired subdivision of the treble strings is accomplished in a simple and effective manner, and that the pressure bar 75 may be readily secured in position, after the stringing of the piano has been completed.

I claim:

1. In a piano, a string plate having a pair of bridges, combined with strings supported 80 thereon, a capo-tasto bar having a pair of flanges resting on the strings, and means for regulating the pressure of the bar against said strings, substantially as specified.

2. In a piano, a capo-tasto bar having a 85 pair of flanges, one of which is stepped, combined with a string engaged by such flanges, said string having a freely vibratile portion intermediate the flanges, substantially as specified.

Signed by me at New York city, (Queens,) 90 N. Y., this 20th day of May 1907.

PETER WEBER.
